TUNING INDICATOR SYSTEM

Richard Keblusek, Huibrech Laban, and Hendrikus Bernardus Ulrich, Eindhoven, Netherlands, assignors to N. V. Philips' Gloeilampenfabrieken, Eindhoven, Netherlands, a corporation of the Netherlands

Application August 5, 1939, Serial No. 288,532
In the Netherlands September 3, 1938

6 Claims. (Cl. 116—124.1)

This invention relates to a wireless receiving set comprising a tuning device having a plurality of main dials for the various wave length ranges. This set is characterised in that it comprises for one or more bands from one or more wave length ranges particular auxiliary dials which are associated with one or more auxiliary pointers and which are substantially longer than the corresponding bands on the main dials and through the cooperation of a screen moving relatively in relation to the tuning device the auxiliary pointer or pointers is or are only visible when the main pointer or pointers cooperates or cooperate with a dial containing the bands under consideration.

A tuning device of this kind may be used with advantage in wireless receiving sets comprising means for the obtainment of the so-called band spreading. Such sets comprise means for enlarging, so to speak, a given wave-band. If a main pointer of the set on one of the main dials indicates a given band, an auxiliary pointer in the set in cooperation with one of the auxiliary dials permits of effecting this tuning accurately. As a rule, the band-spreading means will alone be used in the ultra-short wave region. When in this latter case tuning is effected in the medium wave or long wave range, the auxiliary dials and the associated auxiliary pointer or pointers may give rise to confusion. This is avoided in the set according to the invention by the screen which is relatively movable in relation to the tuning device so that the auxiliary pointer and the auxiliary dial are only visible when the main pointer cooperates with the dial containing the bands under consideration which bands can be enlarged by means of band spreading means provided in the set. It is, of course, possible to cause the screen device to move relatively to the stationary tuning device but preference will generally be given to movable arrangement of the tuning device and to arranging for the non-transparent parts of the set which surround a window in the set to serve as a screening device.

In a favorable embodiment of the set according to the invention the main and auxiliary dials are rectilinear and arranged parallel to each other. It is, of course, also possible to form them into a curved shape. In order to effect tuning as accurately as possible it is preferable, according to the invention, that the auxiliary dials should extend throughout the length of the main dials.

From a constructional point of view it is simple to mount the main and auxiliary dials all on a movable device used in common such as a slide, a drum, a film or the like which is partly visible through a window in the set, the device or devices carrying the main and auxiliary pointer or pointers being so coupled to the device carrying the dials that the auxiliary pointer or pointers

is or are only visible if the main dials jointly with the associated auxiliary dials appear in front of the window.

In a further favorable form of construction of the wireless receiving set according to the invention the movement of the wave length switch has the effect of moving the device carrying the dials and the frame of the pointers to the desired position.

In order that the invention may be clearly understood and readily carried into effect it will now be described more fully with reference to the accompanying drawing.

Figs. 1, 2 and 3 show one form of construction 15 of the wireless receiving set according to the invention and more particularly that part which exhibits the dial, Fig. 1 being a sectional view taken on the line 1—1 of Fig. 2, Fig. 2 being a front elevation, and Fig. 3 being an enlarged partial view of Fig. 2 showing only the scales and pointers which are viewable through the panel window when the receiver is operated in the short-wave range.

The wall 1 of the cabinet has formed in it a window 2. At the back of the wall 1 there are 25 two vertical guides 3 on which a frame comprising bars 4 and 5 is adapted to slide by means of sleeves 6, 7, 8, and 9, said frame carrying a plate 10 which has the various main and auxiliary dials mounted on it. This frame carries in addition a guide 11 for the auxiliary pointer 12. The frame provided with the plate 10 and the auxiliary pointer 12 can be raised and lowered by means of a knob 23 whose rod extends through a slot 24 of the cabinet.

The guides 3 have in addition mounted on them 30 a further frame which comprises bars 13 and 14 and is adapted to slide on the guides 3 by means of sleeves 15 and 16. The bar 13 serves as a guide for the main pointer 29. The sleeves 15 and 16 are provided with an extension 25 and 27 engaging blocks 26 and 28 arranged to be stationary in the cabinet. The cooperation of the extensions 25 and 27 with the blocks 26 and 28 has the effect of determining the lowest position 35 of the frame of the main pointer 29.

The plate 10 has dials 17, 18, 19, 20, 21 and 22 mounted on it. The dials 17, 18 and 19 serve for the long-wave, medium-wave and ultra-short-wave regions. There is a difficulty in tuning stations in the ultra-short-wave range since a comparatively great number of stations are included in a small number of narrow-bands. These bands are indicated in Figs. 2 and 3 by small black 50 blocks on the dial 19. The fact that the set comprises band-spreading means permits of one or more of these bands being extended over a much larger region. For this reason the device according to the invention comprises the auxiliary dials 20, 21 and 22 for the bands 30, 31 and 31a.

In the position of the tuning device shown in Fig. 2 only the dials 17 and 18 and the main pointer 29 are visible through the window 2. Provision is not made of any supplementary auxiliary devices for these dials. If, however, the range of wave-length is changed to ultra-short-wave region and if the knob 28 is raised at the same time, the dials 17 and 18 disappear from the window 2 and are raised and, as shown in Fig. 3, the ultra-short-wave dial (main dial) 19 and the auxiliary dials 20, 21 and 22 become visible. Simultaneously, the sleeves 6 and 8 of the frame of the plate 10 have raised the sleeves 15 and 16 of the frame of the main pointer 29 to such extent that this main pointer cooperates with the ultra-short-wave dial 19. Due to the displacement of the plate 10 the auxiliary pointer 12 has been raised simultaneously and, as shown in Fig. 3, it extends in front of the auxiliary dials 20, 21 and 22. Near the wave band 30 to which the pointer 29 points is shown a given range which corresponds with the auxiliary dial 20. Obviously, this arrangement leads to the advantage that the auxiliary dials and auxiliary pointer are only visible when tuning is effected in the ultra-short-wave region.

What we claim is:

1. A tuning indicator for a radio receiver of the type capable of being tuned to a plurality of wave-length ranges including a short-wave range, comprising a member having formed thereon a plurality of main scales each corresponding to one of said ranges and a plurality of auxiliary scales each corresponding to only a portion of the scale of the short-wave range, a main pointer adapted to selectively cooperate with all of the first mentioned plurality of main scales or with said scales except that of the short-wave range, and an auxiliary pointer adapted to cooperate with said auxiliary scales.

2. A tuning indicator for a radio receiver of the type capable of being tuned to a plurality of wave-length ranges including a short-wave range, comprising a slidable member carrying a plurality of main scales each corresponding to one of said ranges, a plurality of auxiliary scales also carried by said slidable member and each corresponding to only a portion of the scale of the short-wave range, a main pointer in one position of the slidable member adapted to cooperate with all of the first mentioned plurality of main scales and in a second position of said member adapted to cooperate with said scales except that of the short-wave range, and an auxiliary pointer adapted to cooperate with said auxiliary scales.

3. A tuning indicator as defined in claim 2 wherein the receiver is provided with a panel having a viewing window, the slidable member being positioned behind said window and adjustable to selectively expose the short-wave scale and the auxiliary scales or the main scales exclusive of the short-wave scale.

4. A tuning indicator system for a radio receiver of the type capable of being tuned to a plurality of wave-length ranges including a short-wave range, comprising a member carrying a plurality of scales each corresponding to one of said ranges and a plurality of additional scales each corresponding to a predetermined and different portion of the short-wave range scale, a main pointer adapted under certain conditions of operation of the receiver to cooperate with the first mentioned plurality of scales and under other conditions to cooperate with said scales

except that for the short-wave range, an auxiliary pointer adapted to cooperate with said additional scales, a panel of the receiver provided with an aperture and means so constructed and arranged for adjusting the scale carrying member and the pointers relatively to the panel aperture that when the receiver is adjusted to receive wave-lengths other than short-waves only the scales corresponding to said wave-lengths and the main pointer are viewable through the panel aperture, whereas when the receiver is adjusted to receive short-waves, the short-wave range scale, the additional scales and the main and auxiliary pointers are viewable through the panel aperture.

5. A tuning indicator system for a radio receiver of the type capable of being tuned to a plurality of wave-length ranges including a short-wave range and provided with band-spread mechanism when operated in the last mentioned range, comprising a member carrying a plurality of scales each corresponding to one of said ranges and a plurality of additional scales each corresponding to a predetermined and different portion of the short-wave range scale, a main pointer adapted under certain conditions of operation of the receiver to cooperate with the first mentioned plurality of scales and under other conditions to cooperate with said scales except that for the short-wave range, an auxiliary pointer operatively associated with the band-spread mechanism and adapted to cooperate with said additional scales, a panel of the receiver provided with an aperture and means so constructed and arranged for adjusting the scale carrying member and the pointers relatively to the panel aperture that when the receiver is adjusted to receive wave-lengths other than short-waves only the scales corresponding to said wave-lengths and the main pointer are viewable through the panel aperture, whereas when the receiver is adjusted to receive short-waves, the short-wave range scale, the additional scales and the main and auxiliary pointers are viewable through the panel aperture.

6. A tuning indicator system for a radio receiver of the type capable of being tuned to at least a long-wave range and a short-wave range, comprising a member carrying a plurality of parallelly-arranged scales each corresponding to one of said ranges and a plurality of auxiliary scales each corresponding to a predetermined and different portion of the short-wave range scale, a main pointer adapted under certain conditions of operation of the receiver to cooperate with the long-wave and the short-wave scales and under other conditions to cooperate with only said long-wave scale, an auxiliary pointer adapted to cooperate with said auxiliary scales, a panel of the receiver provided with an aperture and means so constructed and arranged for adjusting the scale carrying member and the pointers relatively to the panel aperture that when the receiver is adjusted to receive long wave-lengths only the scale corresponding to said wave-lengths and the main pointer are viewable through the panel aperture, whereas when the receiver is adjusted to receive short-waves, the short-wave range scale, the auxiliary scales and the main and auxiliary pointers are viewable through the panel aperture.
